UNITED STATES PATENT OFFICE.

EDWARD STANLEY, OF BRIDGEPORT, PENNSYLVANIA.

PAPER-BAG MACHINERY.

SPECIFICATION forming part of Letters Patent No. 432,742, dated July 22, 1890.

Application filed June 27, 1889. Serial No. 315,716. (No model.)

To all whom it may concern:

Be it known that I, EDWARD STANLEY, of Bridgeport, in the county of Montgomery, State of Pennsylvania, have invented certain new and useful Improvements in Paper-Bag Machinery, of which the following is a specification.

The object of my invention is to provide a machine for manufacturing what are known 10 as "square bags," or bags with bellows-fold sides; and the invention comprises certain improvements by which I am enabled to produce such bags much more rapidly than has heretofore been possible with the machines 15 now employed.

My invention includes improvements in the various parts of the apparatus. First, in folding devices for forming the bellows folds; second, in cutting devices for severing a partially-folded bag-blank from a continuous 20 web of paper, and, third, in the pasting and folding devices for pasting and folding the bottom lap of the bag. The details of these improvements are fully set forth in the following specification, and they all coact to produce, with rapidity and simplicity of operation, finished bags ready for packing and 25 shipment.

In my improved machine parallel plaits or 30 folds, turned inward and then outward, are formed in each side of a continuous web of paper, which, when thus folded and while in a flat condition, is severed into bag-lengths, and is then further folded to complete the 35 tubular formation of the bag in the same manner as in the manufacture of the ordinary flat bag. The bottom lap is then pasted and folded down in a manner analogous to that practiced in making the common flat 40 bag, but by an improved mechanism, and the completed bag is then delivered from the machine. The general operation of making the parallel folds in a continuous web of paper, then cutting it on the flat, and then folding 45 the flat though partially-folded blank into tubular form, is believed to be new and to distinguish my machine from any heretofore made; and in carrying out this operation I prefer to conduct the web of paper over a central folding-plate, and, by means of side fold- 50 ers, to plait or tuck the paper under the edges

of the central plate, then cut the bag-blank and fold over the central flat portion of the blank on lines parallel with the side plaits or tucks, to form the bellows folds and complete 55 the tubular formation of the bag.

In the accompanying drawings, Figure 1 is a plan view of the mechanism for forming parallel plaits or tucks in a continuous web of paper and severing the bag-blank; Fig. 2, 60 a side elevation of the same; Fig. 3, a transverse section on the line 3 3 of Fig. 1, looking in the direction of the arrows, on a somewhat larger scale; Fig. 4, a plan view showing principally the folding mechanism for completing 65 the tubular formation of the bag-blank, the bottom-pasting devices being removed; Fig. 5, a vertical longitudinal section through the same, including the bottom-pasting devices; Fig. 6, a plan view showing the 70 bottom-pasting devices and a bag-blank in different stages of completion; Fig. 7, a view of the bottom-pasting devices from the rear or delivery end of the machine; Fig. 8, a side elevation of the same; Fig. 9, a vertical longitudinal section of the same on a larger scale, 75 and Fig. 10 a side elevation showing the cutting devices for severing the bag-blanks.

First as to the folding devices. A is the frame of this part of the machine; B, the roll 80 of paper; B', a roll over which the paper passes as it is delivered to the folding devices, and α the web of paper. The central folding-plate C is mounted upon the bed-plate A' by means of a central ridge c on the bed-plate, 85 which lugs c' on the under face of the folding-plate embrace, so as to permit the sliding of the plate endwise, its movement toward the cutting devices being limited by a stop c² at the end of the bed-plate. The end of the 90 plate C toward the feed end of the machine is preferably narrower, it being tapered, as shown by the lines c³. The side folders D D are pivoted at d on each side of the bed-plate, near the feed end of the machine, upon bolts 95 which hold them slightly above the bed-plate, and their rear ends pass under the edges of the central plate C, the relative arrangement of the plates being clearly shown by the full and dotted lines in Fig. 1. They are adjustable upon their pivots in the following manner: Each has a curved slot d', of which the

pivot d is the center, and the bed-plate A' has coincident slots a . A bolt a' passes through both slots, and between the bed-plate and the side folder it has a collar a^2 , which 5 serves to hold the folder above the bed-plate. By means of a nut a^3 on its lower end, beneath the bed-plate, it may be clamped in the bed-plate slot in any desired position. A like nut a^2 on its upper end serves to clamp the side- 10 folder D in any position to which it may be adjusted. The purpose of this arrangement is to permit the adjustment of the bolt a' in such position in the bed-plate that the outer end or wall of the slot in the side-folder will 15 be against the bolt a' when the folder is in proper working position, where it may be clamped by its nut a^2 . When it is desired to move the folders outwardly, as in the threading of the machine, no careful readjustment 20 is necessary, as each folder is merely moved back into position until it is checked by the bolt a' , and is then clamped by its nut. The endwise movement of the central folding-plate C is also provided to give facility in 25 threading the machine and permit the ready removal and substitution of different-sized plates when desired. It may be moved toward the feed end of the machine, and when the paper has been properly adjusted to the 30 folder can be pushed back into the normal position, where it is retained by the draft of the paper. The inner corners of the folders toward the feed end of the machine are curled up, as at d^3 , to assist in forming the side plaits 35 in the paper and avoid any undue strain upon it. The paper web passes up over the roller B', which is formed with a central enlargement B², the width of the central folding-plate, that assists the behavior of the paper 40 web as it passes over the central folder C, and is tucked or plaited under each side thereof by the side folders D. The side folds in the paper and the relation of the paper to the central and side folders are clearly shown in 45 Fig. 3. Rolls E, preferably rubber faced, are mounted upon spring-arms E' on the under side of the bed-plate and press upwardly through apertures in the bed-plate against the side flaps of the paper, pressing it against 50 the under faces of the side folders. These rollers are set at an angle and tend to draw the web of paper outwardly, holding it taut and preventing wrinkles. In threading the machine it is desirable to throw them down 55 out of operation, and this is accomplished by a rod E², projecting laterally from under the bed-plate and sliding endwise in bearings on the under face thereof. It carries two inclined projections or wedges e e, which, when 60 the rod is thrust inwardly, throw the spring plates or arms E', by which the rollers are carried, downwardly. By this mechanism two parallel side plaits or tucks are formed in the continuous paper web—that is, the paper 65 is plaited or folded inwardly and outwardly, as clearly seen in Fig. 3, and by the broken edge of the paper web at the right-hand end

of Fig. 1. In this condition it leaves the folders, one edge passing under a pasting-roll e', Figs. 4 and 5, and the side plaits are pressed flat by two laterally-adjustable rubber-faced rolls F F, revolving by friction mounted upon a shaft and acting in conjunction with a driven bottom roll F'. The rollers F F may be adjusted on their shaft, being secured by 70 set-screws f', to suit different widths of bags, and for the same purpose the central folder C may be removed and replaced by a wider or narrower one, as before mentioned. From the rolls F F' the flat paper web formed with 75 the parallel plaits z passes to the blank-severing devices seen in Figs. 1, 2, and 10. They consist of upper and lower rollers G G'. The serrated knife g, which is of a shape similar to that employed in the ordinary flat bag machine and cuts the edge of the blank in such form as to leave a projecting lip x' to form the bottom of the bag, is carried in one of the rollers and projects therefrom at an angle of 80 about forty-five degrees, the teeth of the knife 85 pointing in the direction of rotation of the roll which carries it. The opposite roll G' has a slot or recess g' in its periphery corresponding in shape to the contour of the edge of the knife and of a depth and width sufficient to permit 90 the knife to enter it without touching. A plate g², corresponding in shape to the edge of the knife g, is secured upon and stands out from the surface of the roll G and projects across the edge of the slot g', the surface of the roll G 95 carrying the knife being flattened at g³, where the knife is mounted to accommodate the plate g² as the rollers revolve. The surfaces of the rolls turn nearly in contact with each other, a space between them being left sufficient to 100 allow the paper free access, and are geared so that their surfaces move at a greater velocity than the paper passing between them. The edge of the plate g³ bends the paper 105 against or over the teeth or serrated edge of 110 the knife and the paper is severed without strain upon it.

The bag-blank is received upon the endless belt H passing under the core-plate H', and is turned or folded over by the scrolls H² in 115 the ordinary manner to complete the tubular formation of the bag, the paper being folded upon the lines y y, Fig. 6—that is, the two folds are made in the flat central web of the blank in line with the inner edges of the side 120 plaits, the side plaits being turned entirely over, as seen clearly in Fig. 6, thus forming a tubular bag-blank with bellows-fold sides. From the scrolls the blank passes under a roll H³ to the bottom pasting and folding devices, 125 shown in detail in Figs. 6, 7, 8, and 9 and constructed as follows:

I I represent the side frame-bars of this part of the machine, and I' I' horizontal side plates upon which sliding mechanism for folding the bottom of the bag and detaching it from the paste-roll travels. A standard K is mounted on each side bar I and supports the journals k of the rocking cradle K', in which the os-

cillating paste-box L is hung. Arms K² depend from the ends of the cradle and are planed out on their faces or socketed, as indicated by the dotted lines, to receive vertical sliding arms M, whose lower ends are pivotally connected at m with vertical ears m' on the horizontal slides J J, whose outer edges are recessed and embrace the inner edges of the horizontal plates I', upon which they slide. The vertical transverse folding-plate N is fastened by its opposite ends to the lugs or ears m' on the slides J J. A detaching-plate O for releasing the end of the bag from the paste-roller l, and under which the bag passes, is pivoted to the slides J J at o o, and has two fingers o' projecting in the direction of the travel of the bag. Springs o² on the slides J J tend to throw this plate downwardly, so as to draw the bag-blank away from the paste-roller, the downward movement of the plate being limited by stops o³ on the slides J J.

P is a driven roll mounted in suitable bearings beneath the paste-box. By means of crank and pitman connections q q' q² this roll in rotating imparts a swinging or oscillating motion to the paste-box cradle, which in turn gives motion to the sliding or telescopic connections K² M, causing the reciprocation of the slides J J. The roll P is provided with a raised portion p, that in each revolution of the roll and oscillation of the paste-box lifts a bag-blank x against the paste-roller l, and a transverse line of paste is printed upon the bag, as shown at l', Fig. 6, to secure the lap or bottom flap x' of the bag when it is folded down.

The roll P, in advance of the raised part p, carries at its ends radially-projecting arms R, in which is mounted a rubber-faced roll r, coacting with the reciprocating folding-plate N to fold the bottom of the bag in the following manner: As the bag-blank x is by the belt H and roll H³ advanced under the detaching-plate O, roll r is just rising to the level of the bed-plate, and the machine being so timed that enough of the tubular blank to form the bottom lap rests on the roll r, the roll lifts the blank against the edge and rolls up the side, Fig. 9, of the folding-plate N, which is coming forward with the same speed, thus turning up the bottom end x' of the bag at nearly right angles, Fig. 9. At this time the raised part p of the roller P lifts the bag and the detaching-plate O, and the paste-roller l prints a line of paste l' upon the bag, as heretofore described. As the roll P continues its movement in the direction of the arrow, the raised part p and the folding-roller r descend, the detaching-plate O throws the bag down out of contact with the paste-roller, and the bag advances between the rollers S S, into whose bite the edge of the bottom fold passes, and the bottom lap is pressed down and the bag completed. In the meantime the slides J J and the paste-box have moved back to the left into position for operation upon the next bag. This arrangement enables me to

produce bags very rapidly. The folding-plate N being held in the same upright position and reciprocating in a horizontal line, does not tear or injure the paper, as it is liable to do when it is attached to an oscillating paste-box which gives a rolling motion to its edge.

No claim is made herein to the method of folding and forming the bag, as such subject-matter is claimed in another application filed by me June 27, 1889, and serially numbered 315,715.

I claim as my invention—

1. The combination of the folding bed-plate, the endwise-sliding central folding-plate movable backward from and forward to the normal working position, and the laterally-adjustable side folder, substantially as set forth. 80

2. The combination, with the central folding-plate having an unobstructed upper surface over which the paper web passes, of the side folding-plates under which the web passes, arranged one on each side of the central plate and having their surfaces below the level of, but parallel with, the surface of the central folding-plate, said side folding-plates acting upon the flat paper web between its center and edges on each side to tuck it under the edges of the central plate, thereby forming flat parallel tucks in the flat web, a roll for supplying the paper web, and mechanism for drawing the flat tucked web continuously forward over and from the central folding-plate, all substantially as and for the purpose set forth. 95

3. The combination, with a central folding-plate mounted by its under surface on the bed-plate, of paper rolls adapted to feed or deliver the paper over the upper surface of said plate, and laterally-adjustable side folders for folding or tucking the paper under the edges of said plate. 105

4. The combination, substantially as set forth, of the bed-plate, the central endwise sliding removable folding-plate mounted thereon, the laterally-adjustable side folders pivoted on the bed-plate, and clamping devices for holding the side folders in the positions to which they are adjusted. 110

5. The combination, substantially as set forth, of the bed-plate, the central and side folders, and angularly-located rollers, as E, bearing against the under sides of the side folders to draw the paper taut laterally. 120

6. The combination, substantially as set forth, of the bed-plate having apertures through which angularly-arranged rollers, as E, work, yielding spring-arms carrying said rollers, a central folding-plate, side folders against the under surfaces of which the rollers work, and mechanism for throwing the rollers down out of action. 125

7. The combination, substantially as set forth, with the coincidently-slotted bed-plate and side folder, of the clamp-bolt passing through both slots, the collar or flange on the bolt between the bed-plate and folder, a clamp-

nut on the under end of the bolt for clamping it in the bed-plate, and a clamp-nut on its upper end for clamping the side folder.

8. The combination, substantially as set forth, with the roll P, having the raised portion p, and carrying the bottom folding-roll r, of the oscillating paste-box and reciprocating bottom folding-plate.

9. The combination, substantially as set forth, of the roll P, having the raised portion p, the oscillating paste-box, the reciprocating sliding frame, and the detaching lever or plate O, pivoted in the sliding frame.

10. The combination, substantially as set forth, with the oscillating paste-box, its roll and the reciprocating frame, of the pivoted detaching - plate for throwing the paper down from the paste-roll, and the transverse upright folding-plate, both mounted on the reciprocating frame, a paper-elevating device for lifting the bag against the paste-roll, and a moving surface or roll, as r, between which and the transverse plate the bottom lap of the bag is folded.

11. The combination, substantially as set forth, of the frame, the standards K K, the paste-box cradle pivoted in the standards, the arms K², depending from the cradle, the slides J J, and the vertical arms M, pivoted on the slides and working in sockets in the arms K².

12. The combination, substantially as set forth, with the blank-feeding devices and the reciprocating frame carrying the transverse bottom folding-plate and the oscillating paste-box, of the devices for pressing the blank

against the pasting-roll and folding the bottom flap against the folding-plate.

13. The combination, substantially as set forth, with the upright bottom folding-plate reciprocating in the direction of travel of the paper and transversely to its own length, of a folding-roller, as r, carried in bearings rotating about a support below the reciprocating plate, the bearings of the roll being so related to said plate that during the operation of folding the bottom flaps the surface of the roll comes opposite the rear face of the plate.

14. The combination, substantially as set forth, with the oscillating paste-box, sliding frame, as J J, and transversely-arranged bottom folding-plate, of a roll or surface, as r, moving in the direction of the folding-plate and coacting with it to fold the bottom of the bag.

15. The combination, substantially as set forth, with the transversely-arranged reciprocating folding-plate, of a roller, as r, having an upward motion toward and behind and a forward motion with the folding-plate, and mechanism for feeding the bag-blank between the two, whereby the bottom lap of the bag is turned up by the roll against the side of the plate.

In testimony whereof I have hereunto subscribed my name.

EDWARD STANLEY.
